UNITED STATES PATENT OFFICE.

FREDERICK HUBBARD, OF EAST BERLIN, CONNECTICUT.

SUPPORTING FOOT FOR LADDERS.

Application filed March 22, 1922. Serial No. 545,832.

To all whom it may concern:

Be it known that I, FREDERICK HUBBARD, a citizen of the United States, residing at East Berlin, in the county of Hartford and State of Connecticut, have invented certain new and useful Improvements in Supporting Feet for Ladders, of which the following is a specification.

My invention relates to improvements in a supporting foot for ladders, being used preferably in pairs, one on each leg of a ladder, the ladder being either of the plain, ordinary form or an extension ladder, and the object of my improvement is to provide a supporting foot structure that can be applied to the lower end of a leg of the ladder and that will serve to prevent the ladder from slipping or sliding when in position for use, and which structure is easily applied to the ladder leg, whether in the factory, on new ladders, or old ladders that are in use, and, furthermore, that provides means for adjustment and changing the active, holding portion that contacts with the ground or pavement so that when one set of prongs or teeth may have become dull another set can be set to the active, holding position.

In the accompanying drawings:

Figure 1 is a front elevation of the lower portion of a ladder that has each of the two legs provided with a supporting foot embodying my invention.

Figure 2 is a side elevation on an enlarged scale of the supporting foot and the adjacent part of the leg, being in part broken away as to the head of the carriage bolt that holds the parts together.

Figure 3 is a front elevation of the same.

Figure 4 is a similar view with the friction disc removed.

Figure 5 is a side elevation of the same.

Figure 6 is a sectional view on the line 6-6 of Fig. 2.

My improved supporting foot for ladders is particularly effective for holding on pavements of concrete and the like and under conditions such that ordinary holding devices that are in common use are unreliable and the means that I provide for effecting this result comprise a friction disc 10 that is applied to the lower end portion 11 of the leg of the ladder 12 and that has the periphery cut to provide teeth 13.

Said disc 10 is made of sheet metal of suitable quality to have the teeth 13 withstand considerable use without becoming

dull and in case from prolonged use it may be desirable to make a change in the teeth I provide means for changing the setting of the disc so that a plurality of sets of 60 teeth can be used as provided on a single disc before the particular disc need be removed.

Furthermore, when said disc is removed the teeth thereon may be sharpened so that 65 it can be used again, in lieu of providing a new disc.

The disc 10 is held in place by means of a bolt 14 that is provided with a nut 15, said bolt 14 passing through the hole 16 in 70 the disc 10 and the hole 17 in the lower end portion 11 of the leg 18 of the ladder 12. The dimensions of the parts are such that the teeth 13 project beyond the outer face portion or border wall 19 of the leg 18 so 75 that said teeth will at all times make contact with the supporting pavement or the like so as to sustain the load of the ladder and provide a friction hold, due to the sharpness of the teeth 13.

In order to positively position the disc 10 relatively to the leg 18 I provide the hole 16 in the form of a non-circular opening that cooperates with a part of the bolt 14 of similar form.

I prefer to use an ordinary carriage bolt for the bolt 14, which has a square portion 20 adjacent the head 21 and to make the hole 16 square to correspond.

Said square portion 20 of the bolt 14 is of 90 sufficient length to project through the disc 10 and enter into the opposed end portion 22 of the hole 17 in the leg 18, the latter being made of wood, as usual.

That is to say, a square socket may be provided in the ladder leg for cooperating with the square portion of the bolt to cooperate in positively positioning the disc relatively to the ladder leg.

I prefer, however, to provide a metal holding plate 23 that is mounted on the side face of the leg 18 of the ladder and is interposed between said side face and the disc 10, and that has a square opening 24 that fits the square portion 20 of the bolt 14.

Said plate 23 may extend upwardly an appreciable distance along the leg 18 and is provided with holding means in the form of a screw 25 to prevent turning.

In use, the bottom portion 26 of the disc 110 will be the part that will sustain the most wear and serve generally as the active por-

tion, and by the construction that is shown and described the disc 10 may be set to a choice of four different settings for a corresponding number of changes of the active portion.

I claim as my invention:—

1. A supporting foot for a ladder comprising a disc having teeth on the periphery and provided with a non-circular hole, a 10 ladder leg having a hole in registration with the hole in the disc, a plate interposed between said disc and leg, having a non-circular hole to correspond to the hole in the disc, and secured to said leg to prevent turning, 15 and a bolt entered into said holes and provided with a non-circular portion for cooperating with the non-circular holes in the disc and plate, whereby means are provided for selectively positioning the disc relatively 20 to the leg so as to permit of the use of different portions of the periphery for the ac-

tive, supporting portion in contact with the ground.

2. A ladder having the legs provided with similar auxiliary supporting feet, said feet 25 comprising each a flat plate that is secured to a side face of the opposed ladder leg and has a non-circular hole, a toothed wheel opposed to said plate and having also a non-circular hole to correspond to the hole in the 30 plate and in registration therewith, the leg having a hole in registration with said non-circular holes, a bolt entered into said holes and provided with a nut, and said bolt having a non-circular portion that fits the non- 35 circular holes in the plate and wheel, whereby the wheel will be positively held relatively to the leg and different parts of said wheel can be used as the active portion for contacting with the ground in supporting the 40 ladder.

FREDERICK HUBBARD.
